UNITED STATES PATENT OFFICE.

JOSEPH LÉON GOBEILLE, OF CLEVELAND, OHIO, ASSIGNOR TO THE ROSS-MORE COMPANY, OF NEW YORK, N. Y., A CORPORATION OF NEW YORK.

DESIGN FOR A WATER AND STEAM BOILER.

SPECIFICATION forming part of Design No. 35,430, dated December 10, 1901:

Application filed November 16, 1901. Serial No. 82,599. Term of patent 7 years.

To all whom it may concern:

Be it known that I, JOSEPH LÉON GOBEILLE, a citizen of the United States, residing at Cleveland, in the county of Cuyahoga and State of Ohio, have invented and produced a new and original Design for a Water and Steam Boiler, of which the following is a specification, reference being had to the accompanying drawing, forming part thereof.

A single view serves to illustrate the design, and this view is a perspective elevation of the boiler complete and showing an artistically-decorated front A and vertically fluted and ribbed sides B, the flutes 2 and ribs 3 alternating and running into the top of the furnace. Otherwise the surface B is plain and straight front to rear and top to bottom, but

rounded somewhat as it rises over the top. At the base of surface B is a vertically-paneled surface C, otherwise even or flush with surface B, and the design comprises all these several features as a whole and consists, essentially, in its appearance with the local peculiarities here and there, as described, entering into the appearance to emphasize its novel character.

What I claim is—

The design for a water and steam boiler, substantially as shown and described.

Witness my hand to the foregoing specification this 17th day of October, 1901.

JOSEPH LÉON GOBEILLE.

Witnesses:

R. B. MOSER,
H. E. MUDRA.
